UNITED STATES PATENT OFFICE.

JEREMIAH M. ALLEN, OF HARTFORD, CONNECTICUT, ASSIGNOR TO THE HARTFORD STEAM BOILER INSPECTION AND INSURANCE COMPANY, OF SAME PLACE.

STEAM-BOILER SETTING.

SPECIFICATION forming part of Letters Patent No. 448,576, dated March 17, 1891.

Application filed November 20, 1890. Serial No. 372,106. (No model.)

To all whom it may concern:

Be it known that I, JEREMIAH M. ALLEN, of Hartford, in the county of Hartford and State of Connecticut, have invented certain new and useful Improvements in Steam-Boiler Settings, of which the following is a full, clear, and exact description, whereby any one skilled in the art can make and use the same.

10 The object of my invention is to provide a furnace that is particularly adapted for burning refuse or like material as fuel in furnaces. It is desirable that the flames from the combustion of the fuel should have as 15 nearly as possible an unimpeded flow from the combustion-chamber, should be evenly distributed over the heating-surface of the boiler, and at the same time should be concentrated and direct in their flow. By the 20 use of a flue or aperture in the bridge-wall of peculiar shape this desirable result is accomplished and the advantages gained in a manner and by means that are free from cumbersome details or expensive features.

25 My invention consists in the combination, in a furnace, of a fire-box and a flue separated by the bridge-wall through which an opening is formed on the outlines of a contracted vein, or, as it is known, a *veina contracta*, all 30 as more particularly hereinafter described, and pointed out in the claim.

Referring to the drawings, Figure 1 is a 35 detail view in lengthwise section through the furnace and the boiler-setting and in side elevation of the boiler. Fig. 2 is a detail view in vertical section through the fire-box. Fig. 3 is a detail view, on enlarged scale in horizontal section, through the flue or opening in the bridge-wall.

40 In the accompanying drawings, the letter A denotes a horizontal steam-boiler installed

in suitable settings with a flue B beneath the boiler and a fire-box extending in front of and beyond the boiler-front. The fire-box is provided with a suitable grate c, door d, and an 45 opening e at the top for the admission of fuel. Between the fire-box and the space beneath the boiler there is located a bridge-wall D, through which there is formed an opening or flue E for the passage of the flames and products of combustion from the fire-box to the combustion chamber or flue beneath the boiler.

In order to provide for a comparatively unimpeded flow of the flames and at the same 55 time insure their comparatively even distribution over the heating-surface of the boiler, this opening is made in the form of a *veina contracta*, as is clearly shown in the several figures of the drawings. The shape of this 60 opening prevents any interference of currents or choking of the outlet or flue, such as would follow from the use of a flue of like area in cross-section that was not made in this peculiar form. By reason of this peculiar construction of the flue a more perfect combustion of the fuel, together with a better distribution of the flames and freer flow, is provided as compared with all of the old forms of flues or openings through the bridge-walls 65 of furnaces of this class.

I claim as my invention—

In a boiler-setting, in combination with a boiler having a combustion-chamber beneath it, a fire-box having a bridge-wall through 75 which a flue is formed on the outline of a *veina contracta*, all substantially as described.

JEREMIAH M. ALLEN.
